SHOTGUN FOREARM

George T. Bradley, Miami, Fla.

Application July 11, 1947, Serial No. 760,298

1 Claim. (Cl. 42—71)

1

This invention relates to improvements in firearms, and more particularly to an improved forearm for an automatic shotgun.

It is among the objects of the invention to provide an improved shotgun forearm formed of a durable, moldable material, such as a synthetic resin plastic, which will not crack or split, wear rapidly or lose its finish and is resistant to temperature changes so that the forearm does not become unduly hot from firing of the gun or unduly cold in freezing weather, which forearm may be fitted to a conventional gun without modification of the gun structure, has securing pins and a gun lubricating fitting permanently molded therein and provides interiorly thereof a space in which to store a gun magazine plug when the plug is not in use in the gun magazine so that the plug will not be lost or misplaced and will always be available when needed.

Other objects and advantages will become apparent from a consideration of the following description in conjunction with the accompanying drawing, wherein:

Figure 1 is a side elevation of an automatic shotgun showing the application thereto of a forearm illustrative of the invention.

Figure 2 is a longitudinal sectional view on an enlarged scale of the forearm illustrated in Figure 1.

Figure 3 is a transverse cross-section on the line 3—3 of Figure 2; and

Figure 4 is a transverse cross-section on the line 4—4 of Figure 2.

With continued reference to the drawing, the conventional gun, illustrated in Figure 1 has a stock 10, breech mechanism 11, barrel 12, and a forearm, generally indicated at 13, underlying the rearward portion of the barrel and abutting at its rear end against the forward end of the breech mechanism 11.

The improved forearm 13 is a hollow body formed of a suitable moldable material of a substantially homogenous character and high structural strength, material such as "Bakelite" or "Formica" having been found particularly suitable for this purpose. The forearm is provided with a longitudinal cylindrical bore 14 extending therethrough which bore receives the recoil mechanism and magazine tubes, not illustrated, of the gun. The upper side of the forearm is open for the major part of its length, as indicated at 15, so that the barrel ring portion of the recoil mechanism may slide lengthwise of the forearm and the upper side of the forearm is concavely grooved throughout its length, as indicated at 16,

2

so that the upper side of the forearm fits closely around the lower side of the barrel 12. Near its forward end the bore 14 is provided with an internal shoulder 17 and from this point to its front end the upper side of the forearm is closed to provide a complete, cylindrical bore which receives and holds the forward end of the gun magazine tube, the end of the tube being closed by suitable closure cap 19.

10 A pair of pins 20 project from the rear or butt end of the forearm and are receivable in holes provided in the forward end of the breech mechanism 11 to assist in holding the forearm in place on the gun. These pins are located one at each side of the opening in the upper side of the forearm and are moulded into the material of the forearm so that they are held firmly and permanently in place.

An elongated opening 21 of somewhat crescent-shaped cross-section is provided in the bottom portion of the wall of the forearm and extends from a location adjacent the shoulder 17 rearwardly of the forearm a distance sufficient to completely receive a three-shell gun plug 22 therein. At its front end the well or recess 21 opens at a transverse shoulder 23 provided in the lower side of the forearm and this open end of the recess 21 is closed by a plate 24 which overlies the open end of the recess and is detachably secured to the forearm by a screw 25 which passes through an aperture in the plate and is threaded into an internally-screw-threaded sleeve 26 embedded in the material of the forearm immediately above the front open end of the recess 21. The gun magazine plug 22 is partly cylindrical in shape and fits into the somewhat crescent-shaped recess 21 so that it can be stored in the gun when not in use and is always readily available when needed.

40 A lubricant fitting, generally indicated at 27, is embedded in the forearm 13 at the upper side of the forearm, and preferably adjacent the front end thereof. This fitting may conveniently comprise a small tube 28, preferably formed of brass or some similar non-corrosive material which extends inwardly and downwardly through the wall of the forearm at an angle of approximately 45° to a plane including the longitudinal center-line of the bore 14 and the longitudinal center-line of the gun barrel 12 so that lubricant, such as gun oil, supplied to the outer end of the tube will fall from the inner end of the tube onto the recoil mechanism located in the bore 14. The tube 28 is provided with lateral extensions 29 which firmly secure it in the wall of the forearm and con-

55

tains a valve ball 30 which is urged by a compression spring 31 into seating relationship with the beaded-over outer-end portion of the tube 28 so that the ball normally closes the outer end of the tube, but may be displaced inwardly by the spout of an oil can to permit the injection of oil into the tube.

The improved forearm is provided externally with longitudinal ribs 32 which extend transversely across the upwardly-tapered forward end of the lower portion of the forearm to provide a firm hand-grip for the gun and is also provided with a pair of longitudinally-extending grooves 33 near the upper side thereof which also facilitate holding the gun in proper firing position.

There is thus provided an improved forearm for an automatic shotgun which forearm is formed of material which will not check, crack or split, or lose its finish because of repeated wettings and contact with scratching or abrasive objects, which is heat-insulating so that it does not become unduly hot in hot weather or upon repeated firing of the gun, and does not become cold enough to cause the hands of a person handling the gun to stick to the forearm even in extremely cold weather, which provides for convenient lubrication of the gun recoil mechanism and also provides a convenient recess or receptacle for the storage of a gun magazine plug to avoid losing or misplacing the plug, and to render the plug readily accessible whenever it is needed.

The invention may be embodied in other specific forms without departing from the spirit or essential characteristics thereof. The present

embodiments are, therefore, to be considered in all respects as illustrative and not restrictive, the scope of the invention being indicated by the appended claim rather than by the foregoing description, and all changes which come within the meaning and range of equivalency of the claim are, therefore, intended to be embraced therein.

What is claimed is:

- A gun forearm comprising an elongated, hollow body having an opening in its upper side to receive the lower portion of a gun barrel, a bore therethrough to receive a gun recoil and magazine mechanism and a magazine-plug-receiving recess longitudinally disposed in the lower portion thereof and spaced from said bore, said recess having one open end, and closure means for the open end of said recess detachably secured to said body.
